UNITED STATES PATENT OFFICE.

ANNA MARGARETHA SCHNEIDER, OF LOS ANGELES, CALIFORNIA.

HOOK AND EYE.

1,037,334.

Specification of Letters Patent. Patented Sept. 3, 1912.

Application filed October 21, 1910. Serial No. 588,255.

To all whom it may concern:

Be it known that I, ANNA M. SCHNEIDER, a citizen of the United States, residing at Los Angeles, county of Los Angeles, and State of California, have invented certain new and useful Improvements in Hooks and Eyes, of which the following is a specification.

My invention relates to garment fastening devices and particularly to that class thereof known as hooks and eyes.

The object of my invention is to provide an improved hook and eye fastener which may be readily attached to the goods without sewing and as readily removed therefrom.

A further object of my invention is to provide a readily removable hook and eye fastener which shall not easily become accidentally detached from the goods or garment.

Other objects will appear hereinafter.

With these objects in view my invention consists generally in providing a hook and eye fastener with attaching means consisting of sharpened prongs formed by sharpening the end of the wire by which the members are made and curving the same outwardly and then inwardly at the point. The points are depressed slightly below the bearing face of the fastening members in order to facilitate attaching the device to the goods or garment.

My invention further consists in various details of construction and arrangements of parts all as will be fully described herein-after and particularly pointed out in the claims.

My invention will be more readily understood by reference to the accompanying drawings forming a part of this specification and in which—

Figure 1 is an illustration of a portion of a garment equipped with two fasteners embodying my invention, Fig. 2 is a side elevation, upon an enlarged scale, of a hook and eye fastener embodying my invention in its preferred form, Fig. 3 is a plan view of the eye member of the fastener, and Fig. 4 is a similar view of the hook member.

Referring now to the drawings 1 indicates the hook member and 2 the eye member of the fastener, each of which is formed of a single piece of wire bent to the required shape. In making the hook a piece of wire

is doubled at the center upon itself forming the close lying parallel portions 3—3 which are again bent transversely of the direction of the first bend 1' as at 1" forming the hook 4 and shank 5. The ends of the wire, which are at the end of the shank, are bent outwardly as at 6 with a well rounded curve terminating in sharpened points or ends 7 which extend inwardly and forwardly toward the shank. The points 7 are preferably depressed below the plane of the shank 5 as shown clearly in Fig. 2.

The eye is formed by bending a single piece of wire to form a well rounded loop 8 at the center which is contracted at the rear end as at 9, and the ends of the wire are curved outwardly as at 10 and then inwardly terminating in the inwardly and forwardly extending pointed ends or prongs 11 similar to the portion 7 of the hook member. The prongs 11 are also preferably depressed a slight distance below the plane of the loop 8. In applying the device to the goods or clothing the prongs 7 and 11 are inserted in the goods at the points where it is desired that the loops 6 and 10 shall ultimately engage the goods and for this reason the points 7 are in direct longitudinal alignment with that portion of the loop mentioned as indicated by the dotted lines in Figs. 3 and 4. In forcing the ends into the goods the goods is slightly stretched as it passes over the extreme outward portion of the curve ends and then resumes its normal. In this way the members are not readily disengaged from the garment accidentally. If the goods are of such a quality as to be injured by stretching, one of the points may be inserted its full distance and then the device turned until the other point is in proper position for entering the goods, after which it is inserted and the fastener turned to proper position. To this end the distance from each point to a point α on the opposite attaching portion, just beyond ultimate engaging position γ , is substantially the same as the distance between the two ultimate engaging points γ — γ .

Having described my invention what I claim as new and desire to secure by Letters Patent is:

In a hook and eye fastener, a fastening member formed of a single piece of wire, and attaching means formed by curving the

ends of the wire outwardly forming ultimate engaged points and then forwardly and inwardly in circular form, terminating in sharp points, the distance between the 5 points being substantially the same as the distance between the ultimate engaging points and slightly less than the distance between each point and the opposite ultimate engaging point so that the points may 10 be successively engaged with the fabric

without appreciably stretching the same, substantially as described.

In testimony whereof I have signed my name to this specification in the presence of two subscribing witnesses.

ANNA MARGARETHA SCHNEIDER.
